UNITED STATES PATENT OFFICE.

CHARLES A. SCOTT, OF OCEANIC, NEW JERSEY, ASSIGNOR OF ONE-THIRD
TO WILLIAM H. EMERY, OF SAME PLACE.

HORSESHOE.

SPECIFICATION forming part of Letters Patent No. 319,749, dated June 9, 1885.

Application filed February 4, 1884. (No model.)

To all whom it may concern:

Be it known that I, CHARLES AUGUSTUS SCOTT, of the town of Oceanic, county of Monmouth, and State of New Jersey, have invented a new and useful Improvement in Horseshoes, which is fully set forth in the following specification.

The annexed drawings will serve to explain the nature and scope of my invention.

Figure 1 represents an ordinary horseshoe on the under side. Fig. 2 represents the form of my auxiliary horseshoe first hereinafter described, the parts being separated. Fig. 3 represents a top view of the shoe and auxiliary shoe when the latter is in position as worn. Fig. 4 represents a bottom view of the shoe and auxiliary shoe when the latter is in position as worn. Fig. 5 represents a modified form of the fore part of the auxiliary shoe designed for use on what is known as a "plain shoe."

When roads or streets are slippery on account of ice or hard snow, or for any other reason, the ordinary method of preventing horses from slipping has been to sharpen the calk or heels of the shoe and the downwardly-projecting toe of the shoe. The objections to this are, that the horse is thereby liable to injure the flooring of his stable and to cut his legs and feet with the sharp points of the shoe. It is also a source of annoyance and expense to have the shoes sharpened, which must be done at short intervals, because the sharpened points of the shoe wear away rapidly. Moreover, these sharpened points, in case the conditions of the ground become changed, are apt to gather balls of soft snow or mud on the horse's hoofs.

My invention remedies these difficulties. It consists of an auxiliary shoe, preferably in two parts, placed on the bottom of an ordinary horseshoe, of such a size that the two pieces can be placed on the under side of the shoe, the rear ends resting against the heels or calks, being the downward projections at the back of the shoe, and the front end resting against the toe or downward projection at the front of the shoe. These two pieces are then fastened together by a screw running through a short

backward projection from the inside of the 50 front of the auxiliary shoe on its inner side, or in any other convenient manner, and they are so arranged and of such a size that when screwed together they are held firmly in place on the horse's shoe by means of two clamps 55 on each side of the auxiliary shoe on the inside and not far from the heels, which run up the inner sides of the shoe and partially embrace the same, and also by two clamps at the front of the auxiliary shoe and on the inner side, which run up the side of the shoe and partially embrace the same. The auxiliary shoe has at the front two sharp downward projections, which, when in position, immediately adjoin the toe of the shoe, but 60 extend a short distance farther down than the toe. These downward projections at the toe should preferably be at right angles to the length of the shoe. At the calks the auxiliary shoe has two sharp downward projections, which immediately adjoin the calks of the shoe, but extend farther down. These 65 sharpened projections may run either parallel to or at an angle to the length of the shoe. The best arrangement, however, of these two 70 sharp downward projections at the rear is, that the inside projection of the auxiliary shoe as worn should run parallel with the length of the shoe, and the like projection on the outside as worn should run at right angles thereto. 75

In the drawings, A represents the ordinary horseshoe, provided with the toe-calk a and heel-calks a'.

B is the two-part auxiliary shoe, provided 85 with the forward pointed projections, b, and the rear projections, c d. The sharp edge of the former is at right angles to the length of the shoe, while that of the latter is parallel therewith. The auxiliary shoe B is secured 90 to the shoe A by the clamps e at the front, and the clamps f at the sides thereof. The said clamps are pressed firmly against the inner edge of the shoe by means of the screw-fastening g. This shoe B can be readily put 95 on and taken off by simply screwing or unscrewing the screw-fastening g, when it can easily be removed; but when screwed it re-

mains firmly in position, the four clamps pressing against the inside of the shoe, and the natural result of the motion of the horse is to cause this auxiliary shoe while in use 5 to expand more than the ordinary shoe, on account of its coming in direct contact with the ground, the shoe itself being protected. Thus the action of the horse tends to fasten the auxiliary shoe more firmly to the shoe itself. 10 It is prevented from slipping forward by the toe or front downward projection, *a*, of the ordinary shoe, as well as by the two front clamps of the auxiliary shoe. It is prevented from moving backward by the calks or rear 15 downward projections, *a'*, of the ordinary shoe, as well as by the rear clamps of the auxiliary shoe, the shoe being generally made narrowing toward the heels.

When the shoe is a plain shoe—that is, has 20 neither corks nor toe, but is smooth all the way round—it will be necessary to somewhat modify the adjustment. The shoe will then be held in position by the four clamps which embrace the inner sides thereof, and these will be sufficient to prevent the shoe from slipping 25 forward; but the position of the rear clamps is such that their action will not be sufficient to prevent the shoe from slipping slightly backward on account of the tendency of the front part of the auxiliary shoe to spread. I prevent this by joining together the two parts of the shoe by a hinge or other suitable means, the hinge being preferably at the extreme front, just behind the toes—that is, the two 30 front sharp downward projections of the auxiliary shoe. It may also be accomplished by means of a coupling, which, when in position, unites the front pieces of the shoe together. The coupling should preferably be attached 35 permanently to one of the pieces of the auxiliary shoe, as shown at *h* in Fig. 5. As shown in said figure, a projection or tongue, *h*, fixed on one of the parts and enlarged at its outer end, enters a deep notch or opening in the other part. The enlargement on the end of tongue *h* prevents the latter from slipping out, while the opening is so shaped as to permit a slight play to the tongue therein.

I have also found it useful to use a fine strip 40 of rubber or leather or other like material between the shoe and the auxiliary shoe, which will prevent the snow or mud from balling.

The number of the clamps, as well as their position, can be somewhat varied without affecting the nature of the invention. The number of the sharp downward projections can also be somewhat varied.

I am aware that removable or secondary horseshoes for attachment to the permanent or fast shoe have been heretofore made or proposed; but all such devices, so far as known to me, differ materially from my invention, and, moreover, present objections which would render them of little or no practical service. For example, a secondary shoe has been made of two parts, hinged together in front, and provided with a screw spanning

the space between the two sides, by which the latter are spread, and lugs thereon caused to enter notches in the fast shoe. The screw, 70 being placed nearer the heel than the toe, would come directly beneath the frog, or most sensitive part of the horse's hoof. It is liable, besides, to be broken or bent, the motion of the foot being such that the screw 75 would strike any stone directly and fairly, and stones are likely to become wedged between it and the frog. For its application, moreover, a special construction of the fast shoe is required. In other auxiliary shoes 80 heretofore devised the screw has been placed at the heel and extending directly across the frog, in which position it is most likely to injure the horse's hoof, and is itself most exposed to damage; in others, the lugs or fastening devices have been placed outside the shoe, where they would be likely to cut the leg; and many of these devices require a special construction of the fast shoe to enable the secondary shoe to be attached thereto. In my 85 invention, on the other hand, the screw is small. It is located near the toe, quite out of reach of the frog, and at which point the motion of the hoof is such that whatever the screw might strike, it would only glance against 90 and not strike fairly. The space between the sides of the shoe is entirely clear, presenting no projections liable either to be broken, to injure the hoof, or to afford lodgment for stones.

What I claim, and desire to secure by Letters Patent, is—

1. An auxiliary or removable horseshoe made in two parts, provided with side clamps and with front clamps, and a screw at the 105 front of said shoe and inside the same, for pressing the clamps against the inner edge of the fast shoe, substantially as described.

2. A two-part auxiliary horseshoe having toe-clamps and side clamps for embracing the 110 inner edge of the fast shoe, a backward extension from the front end of each part, and a screw working in said projections for attaching and detaching the shoe, substantially as described.

3. A two-part auxiliary horseshoe provided with toe and side clamps for embracing the inner edge of the fast shoe and a fastening-screw for spreading the parts, the said parts being connected only at the front ends, so that 120 a clear space is left between the sides of the shoe, substantially as described.

4. An auxiliary horseshoe made in two parts, having toe and side clamps for grasping the inner edge of the fast shoe, and a fastening-screw forming the only connection between said parts, substantially as described.

In testimony whereof I have signed this specification in the presence of two subscribing witnesses.

CHAS. A. SCOTT.
